[57] CLAIM

The ornamental design for an artificial fish lure, as shown and described.

DESCRIPTION

FIG. 1 is a side elevational view of an artificial fish lure with a hexagonal central aperture, showing my new design, the opposite side being a mirror image thereof; FIG. 2 is a top plan view thereof;

FIG. 3 is a cross-sectional view taken along line 3—3 of FIG. 2;

FIG. 4 is a bottom plan view of a second embodiment with a circular central aperture, all other parts being the same as the first embodiment; and,

FIG. 5 is a bottom plan view of a third embodiment with a square central aperture, all other parts being the same as the first embodiment.

The broken line showing of environment in FIGS. 1 and 2 is for illustrative purposes only and forms no part of the claimed design.
